(57) CLAIM

The ornamental design for a seat, substantially as shown and described.

DESCRIPTION

FIG. 1 is a front perspective view of the seat.

FIG. 2 is a rear perspective view of the seat.

FIG. 3 is a top plan view of the seat.

FIG. 4 is a front elevation view of the seat.

FIG. 5 is a left side elevation view of the seat.

FIG. 6 is a right side elevation view of the seat.

FIG. 7 is a rear elevation view of the seat; and,

FIG. 8 is a bottom plan view of the seat.

The broken line disclosure shows different environments and is for illustrative purposes only and forms no part of the claimed design.
